ART OF RECORDING SOUNDS.

Application filed March 14, 1919. Serial No. 282,610.

Our invention relates to various new and useful improvements in the art of recording sounds.

As sound records are now made it is the practice to receive all the sounds in a single recording device, generally in a single horn and by means of a single diaphragm connected mechanically to the cutting or recording stylus. Errors and distortions are inevitable in the making of these records due to the natural resonance of the diaphragm and of the horn, which amplifies and distorts certain sounds. At best the result is a compromise, disturbing effects being minimized as much as possible by the skill of the operator. Usually, after determining what the selection shall be and arranging for its length and tempo to correctly occupy the record, a few bars are played, the sounds being thus recorded, and the test so made is listened to by the director. Then a correction is made; perhaps, some of the instruments may be shifted with respect to others or with respect to the horn or special directions may be given to certain of the musicians to try for some different effect, or in the case of a vocal selection special directions may be given to the vocalist to change his position respecting the horn or to control his voice in some special way; and thereupon another test is made of a few bars, which is again listened to by the director. These tests are repeated over and over again, some times for hours at a time, the instruments being shifted back and forth until the record is as well balanced as possible, and thereupon a finished master is produced. The making of these tests is necessarily expensive and extremely harassing to the musicians and the greatest pains are required on the part of every one.

Furthermore, at the present time, the sounds which are recorded are relatively loud for the musicians and some times as many as six or more vocalists are crowded together into a comparatively small room. This exaggeration is necessary because the present recording devices are relatively insensitive. Moreover, the effectiveness of a recording diaphragm very rapidly falls off as the source of the sounds recedes from the recording device; for example, a sound, which to the ear may not be unpleasantly loud if ten feet from its source, may still

be clearly heard 100 feet away, yet in the case of a recording diaphragm the same sound might be effectively recorded at a distance of 10 feet while at a distance of 100 feet the recording would be so faint as to be inaudible. It is for this reason that in making a sound record all the instruments and the vocalist or vocalists are crowded together around the mouth of the horn. Therefore, the performance of a selection as carried on in a recording laboratory has little or no resemblance to its performance under proper musical conditions in a concert hall for example; there is not the same balance; certain instruments may be played very much louder and other instruments very much less loud. Some instruments, for instance violins, are entirely remodeled to give a proper simulation of the sounds to be recorded, while other instruments, like the piano, have never been satisfactorily recorded. All of these difficulties and defects are obvious to persons having an educated musical sense and are manifested in the records themselves. The fact that these records are as good as they are is due very largely to the skill and experience of the directors who have charge of their making and who have learned through years of experience how to get the best results from the crude and inefficient apparatus with which they work.

With our improvements, it is possible to make records of very faint sounds, so that it is not necessary to do the recording in a small room nor is it necessary that all the performers shall be crowded around the single recording device. Records, in fact, may be made in a concert hall or theatre of the music as it is heard directly by the ear. Sounds which cannot be recorded at all under present conditions may be recorded by means of our improvements, such as the singing of birds or the speech of an orator, who may be a substantial distance away from the recording apparatus, or a theatrical or operatic performance, where it may be impossible to have the recording device on the stage.

One of the obstacles at the present time to combining the talking machine with moving pictures, is the great difficulty of making the records sufficiently loud, and consequently the available space in which an action to be recorded takes place is necessarily

greatly limited. But by means of our improvement sufficiently loud records may be made, even though the source of the sounds is located a substantial distance from the recording apparatus.

We effect these results by causing the sounds to be recorded to actuate a telephonic transmitter or microphone by which the sounds will be converted into current waves and we amplify these waves by means of one or more amplifiers, preferably of the electron relay type, and the amplified waves are then caused to actuate a magnetic receiver which operates the cutting or recording stylus. By using a series of such amplifiers operating successively, any desired degree of amplification may be imparted to the current waves corresponding to the sounds to be recorded and without distortion; in fact, it is possible in this way to amplify sounds to a sufficient extent to make a record thereof when those sounds are practically inaudible. These and many other remarkable results are made possible by the fact that the energy required to operate the recorder is not derived directly from the sound waves, but from a local source of energy controlled by those waves. Thus sound waves of very feeble energy may be used to make a record of any desired intensity without distortion.

With our improvements, it is possible to secure any desired relation of instruments or vocalists to secure the proper balance, without loss of time in making repeated tests, as at present. We effect this result by making use of a plurality of microphones or other transmitters which may be readily moved from place to place so as to occupy any desired position with respect to the orchestra or vocalist, all feeding current waves to the magnetic receiver, and we provide a separate listening phone which the director may carry on his head and which excludes direct sounds. Therefore, the director can listen to the sounds exactly as they are to be recorded and can direct his assistant where to place the several microphones with respect to the musician or vocalist, and, if necessary, give his directions to the musician or vocalist whereby certain desired effects shall be secured, all without the need of making any test whatever and without wasting any time. Thus, the musicians may play through the entire selection, and not merely a few bars thereof, during which time the director by causing the microphones to be shifted in various ways may secure what he considers to be the proper balance. Or the desired balance may be secured without moving the microphones by adjusting their respective amplifications.

The composite currents from the several microphones all feed into a common receiver circuit and thus actuate the recorder magnet with a resultant effect due not to any

one microphone but to all of them in combination, and the listening phone when used will be influenced by the same resultant effect, so that the director hears, not the current waves from one microphone, but the resultant effect of all the current waves, precisely as recorded. These composite currents may be amplified by a single amplifier or by a series of amplifiers working successively; or a separate amplifier or series of amplifiers may be employed for each microphone. Means are preferably employed for controlling the degree of amplification, all of which may be located near the director, who, by means of his listening phone, may himself thus control the recording to a large extent to secure the desired effect. In this way also, the director can have in his control the vocal sounds produced by an artist and can properly cut them down if too loud or amplify them if not loud enough, whereas at the present time, in such an event the director must signal the artist to recede from or approach the horn. In fact, in many cases at present the director stands with his hand on the artist's shoulder and pushes him forward or back, towards or away from the horn as his judgment may indicate, but he has no means of knowing what the result may be until a test is made from the actual record. With our improvements, the director at all times by means of the listening phone knows precisely the relation between the vocal sounds and the instrumental sounds, and has means for instant control or adjustment.

With our improvements, we are able to substantially reduce the distortions now due to resonance in the recording diaphragm, which, as is well known, produces peaks or amplification corresponding to certain tones. This result is achieved when a number of diaphragms are used by making the diaphragms dissimilar—such as of different size or thickness of material—so that the resonance points will not correspond, and hence the recorded sound will not be characterized by such extreme distortions as when a single recording diaphragm is used. The same effect can be secured in minimizing the distortion due to horn resonance, that is to say a number of dissimilar horns may be employed whereby the resonant periods of one will not correspond with those of any other. Or the horns may be omitted altogether, since any desired record intensity may be secured without them.

In order that our invention may be better understood attention is directed to the accompanying drawings forming a part of this specification, and in which Fig. 1 is a diagram showing our invention as carried out with a single microphone and two successively operating electron amplifiers. Fig. 2 is a diagram showing the invention as used with

four microphones all feeding into a common parallel circuit with a single amplifier and a listening phone in the circuit of the magnetic recorder. Fig. 3, a corresponding view 5 showing three microphones, each having an electron amplifier, and with the controlling devices for regulating the amplification all located near a common point so as to be within the control of the director. Fig. 4, 10 sectional views showing three separate diaphragms and three separate horns, the dissimilarity of the diaphragms being secured by varying their diameter and the dissimilarity of the horns being secured by varying 15 their size. Fig. 5, a corresponding view showing three dissimilar diaphragms, the dissimilarity being secured by varying the thickness of the diaphragms. Figs 6, 7 and 8 represent conventional curves of response 20 of three different diaphragms to sound waves of different frequencies showing the peaks due to resonance of the diaphragms, but the peaks corresponding to notes of different pitch in the three diaphragms. The three 25 curves indicate that the sounds represented thereby were of substantially the same amplitude. Curves of response of this general character are shown at *a*, *b*, *c* in Fig. 117 (page 149) of a book entitled "The Science 30 of Musical Sounds" by Dayton C. Miller (New York; The MacMillan Co., 1916). According to this book the three curves in Fig. 117 represent the "responses of three glass 35 diaphragms of 22, 31 and 50 millimeters diameter, respectively." Fig. 9 is a composite diagram illustrating the effect of combining the current waves produced by the three diaphragms of Figs. 6, 7 and 8 respectively, illustrating how the distortion is reduced by 40 such combination. Fig. 10, a detail view illustrating a distortionless magnetic receiver or recorder, without a diaphragm. In all of the above, corresponding parts are represented by the same reference numerals.

45 Referring first to Fig. 1, the microphone or other transmitter 1 is of any suitable standard type, being provided with a horn 2 of any suitable material for collecting the sounds and directing them to the mouth piece 50 of the microphone. The microphone and horn should be designed for accurate rendering of tone values rather than for high sensitivity, as any desired intensity of record may be secured by the amplification. The 55 current waves from the microphone, by means of transformer coils 3, 3', are fed to an electron amplifier 4, having familiar circuit connections, by which the current waves will be amplified. From this amplifier, by 60 means of coils 5, 5', the amplified current waves are directed to a second amplifier 6 where a further amplification takes place. Obviously as many of these amplifiers may be employed as may be needed to secure the 65 desired degree of amplification. From the last amplifier in series, by means of coils 7, 7', the amplified current waves are fed to a receiver circuit 8, in which is located a magnetic recorder whose coils 9 actuate a diaphragm or armature 10, which operates the 70 link 11, to which is connected the cutting or recording stylus 12, which impresses the record on a disc or cylinder of recording material. The record may obviously be of the laterally undulating or vertically undulating 75 type. It will be seen that sounds received by the microphone 1 will be amplified by the amplifiers 4 and 6 and that the amplified current waves will actuate the magnetic receiver and cause the cutting or recording 80 stylus to be actuated in accordance with the original sounds, but to any desired amplified extent depending upon the degree of amplification.

85 Referring to Fig. 2, we show four microphones all feeding in parallel to a common receiving circuit. Thus this receiving circuit will be influenced by the current waves from all the microphones. The composite current thus developed will be amplified by 90 the electron amplifier 15 and the amplified composite current will flow through the receiving circuit 8 to actuate the magnetic recorder. It will, of course, be understood 95 that instead of using a single amplifier 15 a plurality of such amplifiers may be employed for amplifying the composite current, as illustrated in Fig. 1. 16 represents a listening phone connected to the receiving circuit 8. This listening phone may be carried by the director and is preferably arranged to exclude direct sounds, so that the director may listen at all times to the resultant sound waves from all the microphones 100 which influence the magnetic receiver. The several microphones 1 (Fig. 2) are preferably movable from place to place, so that they may be located at any desired points with respect to the orchestra or vocalist. The director gives his directions to his assistants as to where these microphones shall be placed, so as to secure the required balanced 105 effect as will be understood.

110 Referring to Fig. 3, we show three microphones, each provided with a separate electron amplifier 17 by which the current waves from each microphone will be amplified. Through transformer coils 18, 19 and 20 shown as arranged in series, these amplified current waves are fed to the receiving circuit 8 so as to influence the magnetic recorder. The listening phone 16, as in Fig. 2, is connected to the recorder directly so that 115 it will be influenced by the composite amplified current from all the microphones and the director may thus know exactly what is being recorded. The potentiometers 21, 22 and 23 of the several microphones are all located near a common point within reach 120 of the director, so that he may himself con-

125

130

135

trol the degree of amplification of one or all of the microphones. Preferably the diaphragms of the microphones are made purposely dissimilar; for example, by varying 5 their diameter, as shown at Fig. 4, or by varying their thickness, as shown at Fig. 5, and preferably also the horns are made purposely dissimilar; for example, by varying 10 their size as shown at Fig. 4. The importance of using dissimilar diaphragms and dissimilar horns will be obvious from inspection of Figs. 6, 7 and 8, which show the curves of response of diaphragms of different diameters. With these diaphragms it 15 will be noted that peaks are formed, corresponding to certain tones, and representing abnormal increases in amplitude. If, therefore, an ordinary recorder were used with a diaphragm having the characteristics 20 of Figure 6, whenever a sound is recorded corresponding to its responsive tone, or in its immediate neighborhood, it will be greatly distorted in the record.

By the use of the present invention, combining the responses of the three diaphragms 25 to cause them to feed the current waves into a common circuit, the resultant, influencing the magnetic receiver, will correspond to the diagram of Fig. 9, in which it will be noted 30 that the peaks are relatively diminished. In other words, in the case of the individual diaphragms the peaks represent a distortion in amplitude of substantially one hundred per cent, whereas when the effects of the 35 three diaphragms are combined the peaks as shown in Fig. 9 represent a distortion of only about thirty-three per cent. It will be understood that by employing a separate amplifier for the several transmitters as 40 shown in Fig. 3, the amplitude of the curves of response from such diaphragms may be brought to any desired value so as thereby, to secure the best effects due to the combination of currents from the three diaphragms 45 in reducing the distortion due to resonance. In other words, if three curves of response, corresponding to *a*, *b* and *c* in Professor Miller's book, are combined, the curve *c* is of so much greater amplitude than of *a* or *b* 50 that the combination of the three gives a very slight increase in the general body of the tone, but by amplifying electrically the responses of *a* and *b* to bring these curves up to a value comparable to that of *c*, the 55 beneficial effect described will be secured. The same thing is true in the case of the horn, which, as is well known, also has natural periods of resonance, but by using dissimilar horns these resonant peaks may 60 be flattened out in the same way as when using dissimilar diaphragms. Or the horns may be omitted altogether, depending on the amplifiers to give the requisite record intensity. Of course, when only three microphones are used there may still be substan-

tial peaks or amplifications due to resonance, but by using a considerable number of microphones, for instance eight or ten, these disturbances due to resonance may be practically eliminated so as not to be detected in the finished record. 70

Inasmuch as the motion of the recorder stylus is controlled, not by direct mechanical action of sound waves but by an electric current, it is not necessary to use a diaphragm in the recording apparatus. The recorder stylus may be operated by any suitable device capable of translating an electric current into motion. It is thus possible to use devices whose action is remarkably free 80 from distortion of the wave form. For example, the armature of the recorder magnet may be carried by any suitable yielding supporting means, such as a spring. This supporting means should be such that it will 85 not give the armature a natural vibration period within the audible limit.

One form of recorder is shown in Fig. 10, and comprises an armature 10 carried by a stretched wire 24, operating the stylus 12 through the link 11. The stretched wire 24 is provided with a screw 25 for adjusting its tension. By making the armature light and the tension of the elastic wire relatively high 95 the natural period of vibration of the device may be made above the limit of audible sound, so the response of the recorder to sound vibrations will be practically distortionless.

Obviously it is not necessary to use microphones for picking up the sound waves. Any suitable form of sound-responsive electrical generator or transmitter may be used: for example, an electromagnetic transmitter, in which the motion of a diaphragm 100 relative to a magnet produces current vibrations in the magnet coil through variations in the reluctance of the magnetic circuit. Such devices possess certain advantages, for although less sensitive than microphones 105 they may be made extremely free from wave form distortions.

The expression "cutting or recording stylus," as used by us in the following claims, is intended to refer to a device having the 115 capacity of bodily removing the material of the blank on which the record is formed or indenting or displacing the blank material in the formation of such record, or the making of a record by the injection of 120 an extremely attenuated wax thread on a metallic surface, or the making of the record magnetically in steel, as proposed by Poulsen, by the direct action of a magnet operated by the amplified currents or in any 125 other suitable way, our invention not residing in details having to do with the physical formation of the record but only with the means by which the record forming device is actuated.

Having now described our invention, what we claim as new therein and desire to secure by Letters Patent is as follows:

1. In the art of recording sounds, the combination of a series of telephonic transmitters for receiving the sounds to be recorded and converting them into current waves, means for separately controlling the amplitude of the current waves from each transmitter, and a receiver operating the cutting or recording stylus and actuated by the current waves from the several transmitters, substantially as set forth.
2. In the art of recording sounds, the combination of a plurality of telephonic transmitters for receiving the sounds to be recorded and converting them into current waves, means for separately controlling the amplitude of the current waves from each transmitter, a receiver operating the cutting or recording stylus and actuated by the current waves from the several transmitters, and a listening phone located in proximity to said controlling means and also actuated by the current waves from the several transmitters, substantially as set forth.
3. In the art of recording sounds, the combination of a plurality of telephonic transmitters for receiving the sounds to be recorded and converting them into current waves, said transmitters being separately movable with respect to the source of said sounds, and a receiver operating the cutting or recording stylus and actuated by the current waves from the several transmitters, substantially as set forth.
4. In the art of recording sounds, the combination of a plurality of telephonic transmitters for receiving the sounds to be recorded and converting them into current waves, said transmitters being separately movable with respect to the source of said sounds, a receiver operating the cutting or recording stylus and actuated by the current waves from the several transmitters, and a listening phone also actuated by the current waves from the several transmitters, substantially as set forth.
5. In the art of recording sounds, the combination of a plurality of telephonic transmitters for receiving the sounds to be recorded and converting them into current waves, said transmitters being separately movable with respect to the source of said sounds, means for separately controlling the current waves in each transmitter, and a receiver operating the cutting or recording stylus and actuated by the current waves from the several transmitters, substantially as set forth.
6. In the art of recording sounds, the combination of a plurality of telephonic transmitters for receiving the sounds to be recorded and converting them into current waves, said transmitters being separately movable with respect to the source of said
7. In the art of recording sounds, the combination of a plurality of telephonic transmitters for receiving the sounds to be recorded and converting them into current waves, said transmitters being separately movable with respect to the source of said sounds, means for separately controlling the current waves from each transmitter, said controlling means being located near a common point, and a receiver operating the cutting or recording stylus and actuated by the current waves from the several transmitters, substantially as set forth.
8. In the art of recording sounds, the combination of a plurality of telephonic transmitters of different resonant characteristics for receiving sounds to be recorded and converting them into current waves and a receiver operating the cutting or recording stylus and actuated by the current waves from the several transmitters, substantially as set forth.
9. In the art of recording sounds, the combination of a plurality of telephonic transmitters of different resonant characteristics for receiving sounds to be recorded and converting them into current waves, an electron amplifier for amplifying the current waves, and a receiver operating the cutting or recording stylus and actuated by the current waves of the several transmitters, substantially as set forth.
10. In the art of recording sounds, the combination of a plurality of telephonic transmitters of different resonant characteristics for receiving the sounds to be recorded and converting them into current waves, an electron amplifier for amplifying the current waves, means for controlling the amplifying effect of the amplifier, and a receiver operating the cutting or recording stylus and actuated by the current waves from the several transmitters, substantially as set forth.
11. In the art of recording sounds, the combination of a plurality of telephonic transmitters, having diaphragms of different resonant characteristics for receiving the sounds to be recorded and converting them into current waves, and a receiver operating a cutting or recording stylus and actuated by the current waves from the several transmitters, substantially as set forth.
12. In the art of recording sounds, the

combination of a plurality of telephonic transmitters, having diaphragms of different resonant characteristics for receiving the sounds to be recorded and converting them into current waves, an electron amplifier for amplifying the current waves, and a receiver operating the cutting or record-

ing stylus and actuated by the current waves of the several transmitters, substantially as set forth.

10

This specification signed and witnessed this 13th day of March, 1919.

FREDERICK K. VREELAND.
